UNITED STATES PATENT OFFICE.

DANIEL E. HORTON, OF BUFFALO, NEW YORK.

EXCAVATOR.

SPECIFICATION forming part of Letters Patent No. 451,484, dated May 5, 1891.

Application filed August 7, 1890. Serial No. 361,335. (No model.)

To all whom it may concern:

Be it known that I, DANIEL E. HORTON, a citizen of the United States, residing in Buffalo, in the county of Erie and State of New York, have invented certain new and useful Improvements in Excavators, of which the following is a specification.

My invention consists in certain improvements in excavating-machines for excavating cellars or for other purposes, all of which will be fully and clearly hereinafter described and claimed, reference being had to the accompanying drawings, in which—

Figure 1 is a sectional side elevation. Fig. 2 is a front elevation. Fig. 3 is a detached sectional side elevation of the double snatch-block. Fig. 4 is a front elevation of the same. Fig. 5 is an enlarged elevation of a portion of the rocking frame, showing the device for securing the weight connected with it when drawn down. Fig. 6 is a side elevation of the releasing-hook in its holding position. Fig. 7 is a side elevation of the excavating apparatus complete. Fig. 8 is a front elevation of the releasing-hook; and Fig. 9 is a side elevation of the same, showing it open in condition for releasing the earth-scraper.

In said drawings, 1 represents the stationary portion of the frame-work. It is firmly secured in position in the usual way to the horizontal or foundation frame 2 by braces 3. There are two of these frames placed directly opposite each other, one at each side of the foundation-frame 2. Directly in front of the stationary frame-work is jointed to plates 4 by pins 5 a rocking frame 6, having the upper portion 6^a, securely fastened together in the usual way and strengthened by diagonal braces 7. At the rear upper end of the stationary frame-work on one side is a block 8, on which is mounted in suitable bearings a grooved friction-roller 9. This frame-work is preferably made of wood as the most suitable material; but any other suitable material may be used.

To the rocking frame is secured a cable 10 by means of an eyebolt 11. (See Figs. 1 and 7.) This cable passes horizontally, or substantially so, over the top of the stationary frame, and then over the grooved roller 9, and is then secured to a weight 12. This construction allows the rocking frame to be

turned forward, as shown in Fig. 7 and by the dotted lines in Fig. 1. By this construction it will be seen that when this rocking frame 55 is released from the force that rocks it forward it will be immediately returned to its vertical position by the weight 12, being stopped by coming against the projecting ends of the upper horizontal stationary frame- 60 pieces 3^a.

In Fig. 1 I have shown a forwardly-projecting frame-piece 13, strengthened by diagonal braces 14. This construction brings the weight-supporting portion forward; but it is 65 not material, as either construction can be used.

To one side of the top 6^a of the rocking frame 6 is mounted in a block 15 a grooved friction-pulley 16, and in the center of the 70 cross-frame piece 6^a is another block 17, on which is mounted another grooved friction-roller 18. Over the friction-rollers 16 and 18 is passed a chain or cable 19, having a weight 20 on the portion which passes down over the 75 friction-pulley 16. This weight 20 is provided with two projecting lugs 21, through which the guide-rod 22 passes. This guide-rod 22 keeps the weight 20 always in line with the frame 6. At the bottom of the weight 20 80 is a downwardly-projecting swinging portion or eye-piece 23, jointed to the weight by a pin 24, and at the foot of the post 6 is an outwardly-projecting catch-piece 25. By this construction it will be noticed that when the 85 weight is down to its lowest point the swinging eye-piece 23 may swing over the projecting catch 25, and thus be securely held down until released by turning the swinging piece off. When the weight 20 is not supported by 90 a vertical rod 22, a stationary eye-piece 23^a may be attached to it, the weight in this case being moved to fasten it. At the opposite end of the cable 19 is secured a double snatch-block 26, having an eye-piece 26^a, (see Figs. 95 3 and 4,) by which it may be secured when down by means of the pivoted catch 27, which is held up by a spring 28, so that the catch can be released by the foot when required. The snatch-block 26 is provided with two 100 grooved pulleys 27^a. (Shown in Figs. 3 and 4.)

To the drum 29 of a double-drum hoisting-machine of any well-known construction is secured a cable 30, (see Figs. 1 and 7,) which

passes through the snatch-block 26 between the two grooved rollers 27^a. At the opposite end of this cable is attached an earth-scraper 31 by means of a hook 32, and above the hook 32 is a clamp 33 to prevent the cable from being drawn through the snatch-block. The hook 32 hooks into a ring in a bail or short connecting-piece of cable 34, secured to the rear of the scraper, and at the opposite end 10 of the cable 34 is secured a releasing-hook 35. The construction of this releasing-hook is better shown in Figs. 6, 8, and 9, 35 being the main or body portion of the hook, which is provided with an eye-piece 36. 15 To the lower forwardly-projecting portion 36^a of the part 35 is pivoted the movable hook portion 37 by a pin 38, and to a projecting portion 39 on the hook portion 37 is pivoted one part 40 of a toggle-joint, to which the 20 other part 40^a of the toggle-joint is pivoted by a pin 41, having its opposite end pivoted to a downwardly-projecting piece 42 on the portion 35 by a pin 43. At the back of the pivoted partial hook portion 37 is a backward 25 and upwardly curved projecting portion 44. (Shown in Fig. 9.) The object of this construction is to allow the bail 44^a of the earth-scraper 31 to slip off when the part 37 is turned over in the position shown in Fig. 9, 30 when it is desired to dump the earth-scraper, a rod or piece of cable 45 (see Figs. 7 and 9) being connected to the toggle-joint and provided with a hand-stirrup 46, (shown in Fig. 7,) by which it may be operated. The toggle-joint is connected by a spiral spring 47 with the portion 35, so that the moment the rod 45 is released it will immediately resume its normal position, as shown in Fig. 6, in which position the hook is held rigidly in its holding 35 position, as shown in said figure, until opened by operating the toggle-joint, as above set forth. At the rear of the earth-scraper is another cable 48, which passes back therefrom (see Fig. 7) and from thence over a stationary 40 snatch-block 49, which is secured to a stationary holding-post 50 or other equivalent holding device. From thence it passes back again over the base or platform and is attached to the other drum 51 of the hoisting-machine. 50

The operation is as follows: The rocking frame 6 being in the position shown in Fig. 1 and the earth-scraper being drawn back as far as may be required by means of the drum 51, which turns in the direction of the arrow *f* and winds up the cable 48, the drum 29 running loose while this operation is going on, at the same time the double snatch-block 26 is held down, as shown in Figs. 1 and 2, by the catch 27. (See Fig. 2.) The drum 51 is now released (so as to run loose) in the usual and well-known way, and the drum 29 is brought into action, turning in the direction of the arrow *e*, which operation draws the 65 scraper 31 back, (it being held in the proper position to scoop up as much earth as it will carry.) When the scraper is moved directly

under the top of the rocking frame 6 and 6, the double snatch-block 26 is now released from the catch 27, and it is drawn up, carrying the loaded earth-scraper with it by means of the cable 19, the portion outside of the rocking frame being drawn downward until the weight 20 may be secured to the catch 25, as above mentioned. The loaded scraper is 75 now in the position shown in Fig. 7, the drum being still in motion. As soon as the clamp 33 reaches the snatch-block 26, and as it will not pass through, it draws the frame 6 and 6 forward, as shown, when the action of the 80 drum 29 is instantly stopped by the operator in the usual way and the load in the scraper is ready to be dumped, as before mentioned, into a wagon which may be drawn under it. The weight 20 is now released and the double 85 snatch-block secured by the catch 27, as before. The frame 6 and 6 is now drawn by the weight 12 to a vertical position, as shown in Fig. 1, so that it rests against the front 90 ends of the horizontal beams 3^a, and the same operation above described may be continually repeated, the earth-scraper passing back and forth until the desired excavation is completed. 95

I claim as my invention—

1. In an excavating-machine, the combination of a stationary frame portion, a pivoted rocking supporting-frame kept in a vertical position against the stationary frame by a weighted cable connected to it and passing over a pulley on the stationary frame, a double snatch-block connected to a cable passing over pulleys on the top of the rocking frame, then down and connecting with a weight having a fastening device by which it can be secured when the double snatch-block is drawn up, a cable passing through between the two grooved pulleys in the snatch-block and connecting with the rear end of an earth-scraper on one side of the 100 snatch-block and with one of the double drums of a hoisting-machine on the other side, a releasing-hook connected with the front portion of the scraper, and a cable connected with the under rear end of the scraper 105 and extending back to a snatch-block secured to a stationary support, around which it passes forward to the other roller of a double-drum hoisting-machine, substantially as and for the purposes described. 110

2. In an excavating-machine, the combination of a stationary frame with a pivoted weight-supported rocking frame, a cable connected thereto, passing over a friction-pulley on the stationary frame, and provided with a 115 weight to keep the rocking frame in its normal vertical position, and a means, substantially as above described, for drawing the load up toward the top of the rocking frame and then drawing the frame forward, so as to bring the load over a wagon in position to be dumped, after which it is brought to its normal position, substantially as described. 120

3. In an excavating-machine, the combina-

tion, with the suspended earth-scraper, of a releasing-hook having a pivoted hook portion kept to its normal position by a toggle-joint and spring, and a rod for opening it, substantially as described.

5. In an excavating-machine, the combination, with the rocking supporting-frame, of a weighted cable for bringing it to its normal position, a double snatch-block having two

grooved pulleys between which the cable carrying the earth-scraper passes and is supported either in its upper or lower position, and said cable, substantially as described.
